UNITED STATES PATENT OFFICE.

THOMAS C. CRAVEN, OF NEWARK, NEW JERSEY.

COMPRESSOR FOR AIR AND GASES.

SPECIFICATION forming part of Letters Patent No. 451,460, dated May 5, 1891,

Application filed June 7, 1890. Serial No. 354,544. (No model.)

To all whom it may concern:

Be it known that I, THOMAS C. CRAVEN, a citizen of the United States, residing at Newark, in the county of Essex and State of New Jersey, have invented an Improvement in Compressors for Air and Gases, of which the following is a specification.

Great difficulty has heretofore been experienced in pumping air and other gases when under a very high pressure, because the expansion of the air either in the cylinders or the passage-ways frequently prevents the drawing in of a fresh supply upon the back-stroke, and the compression of the air in the cylinder at the end of the stroke is often but little more than the pressure of air in the reservoir into which such air is forced.

In my present invention I make use of a pump that acts upon the water or similar fluid, and this water is automatically directed into one or two cylinders or chambers and displaces the air therein, forcing the same out from the vessel and into a receiving-chamber after the pressure has accumulated sufficiently to pass by the retaining-valves, and when one cylinder is full of liquid the connections are automatically changed to the other cylinder and the operations are repeated therein, while the water is allowed to

run out of the first cylinder and atmospheric air to pass in and take its place, so that this cylinder is ready for the air to be compressed therein, when the automatic mechanism is again shifted from one cylinder to the other.

In the drawings, Figure 1 is a plan view at the line xx of Fig. 3. Fig. 2 is a vertical section at the line yy , Fig. 1; and Fig. 3 is a vertical section at the line zz of Fig. 2, showing also the upper portions of the air-cylinders and valves in section. Fig. 4 is an elevation of one of the float-valves.

The air-cylinders A B rest upon and are bolted to the base-plate C, and below this base-plate or within the same is the valve-chest D with a cover 2, and within the valve-chest is the frame E around the valve F, and there are ports 3 and 4 in the valve-seat leading to the respective cylinders A and B, and there is an exhaust-port 5 leading to the discharge-pipe G. The valve F is represented as an ordinary **D** slide-valve, as the same is

best adapted to this apparatus; but I do not limit myself in this particular.

The water-supply pipe H leads from any suitable water-pumping apparatus to the valve-chest D, and by the valve F water is directed through the port 3 to the cylinder A or through the port 4 to the cylinder B, according to the position of the valve.

At the top ends of the respective cylinders A and B are valves I within the conical heads K of the respective cylinders, and at the apex of each conical head is a check-valve 6 at the junction of such conical head K with the branch pipes L, leading to any suitable air-holding vessel or accumulator. It is preferable to place an adjusting-screw 7 over each of the check-valves 6 to limit the movement of such valve, the said adjusting-screw passing through perforated bridge pieces or disks, and I remark that it is preferable to have upon each valve 6 a cylindrical stem 8 to the valve, the same sliding within the cylindrical or tubular portion at the apex of the conical head, and this cylindrical portion is channeled upon its edges up to the valve, the channel being sufficiently large for the free passage of the air under pressure as it is forced from the cylinder A or the cylinder B into the branch pipe L.

Each of the valves I is conical in its external configuration, and the stem 9 passes through and is guided by the bridge or perforated disk 10, so that the valve when open rests upon such bridge 10, and in order to close the valve a float 11 is provided for each valve, which is usually conical and held between strips or basket-shaped supports 13 from the valve I, and I prefer to make the float 11 of cork.

Upon the valve-frame E and at opposite ends thereto are the rods 13 and 14, passing through stuffing-boxes 15 at the ends of the valve-chest D, and at each end of the valve-chest and in line with the same are cylinders M N, containing valve-moving pistons O and P, that are preferably provided with cup-leathers and permanently connected to the respective rods 13 and 14, and there are pendulous levers Q, pivoted at 16 and provided with weights R, and these pendulous levers are connected by link-joints 17 and 18 to the

valve-moving pistons O and P, respectively, and in line with the rods 13 and 14, and there is a hole 19 passing from the cylinder A into the cylinder M and a similar hole 20 from the cylinder B into the cylinder N, and these cylinders M and N remain full of water between the valve-moving pistons O P and the ends of the valve-chest D. The valve-chest D also remains full of water, and the operations of the parts are as follows:

Water being forced through the supply-pipe II by competent power applied to a pump, such water is admitted by the valve F to one of the ports 3 or 4. In Fig. 1 the water is represented as passing by the port 3 into the cylinder A, and as the water rises in such cylinder the air above it is compressed, and when the pressure of the air becomes equal to the pressure of the air in the branch pipes L the valve 6 opens and the air under pressure continues to pass into such branch pipes L and the container or accumulator, and when the water rises around the float 11 the water lifts such float and closes the valve I, so that water does not pass into the pipes L, and the water in the cylinder A being now confined the pressure accumulates and the water passes through the hole 19 into the cylinder M, and the pressure becomes sufficient against the valve-moving piston O to move the same along in the cylinder M against the action of the pendulous levers Q and weights R, and the frame E is moved at the same time, and the weights pass over the pivots of the pendulous levers shortly before the end of the frame E comes in contact with the valve, and as the pendulous levers Q and weights fall in the other direction the valve F is moved and the water admitted to the cylinder B through the port 4. During the foregoing operation the water in the cylinder B has been running out by gravity because the valve F has opened a passage-way between the port 4 and the exhaust-port 5, and during this operation the valve 6 to the cylinder B has been closed; but air is admitted into such cylinder B as the water runs out in consequence of the check-valve S, of any suitable construction, opening inwardly and connected with the cylinder B or its conical head K, and the supply is such as to allow the cylinder B to become emptied, or nearly so, by the time the cylinder A has become filled and the valve changed, as before mentioned, and after the valve has been changed the water under pressure passes by the port 4 into the cylinder B, the check-valve S closes, and as the water accumulates and the pressure increases the valve 6 to the cylinder B is opened and the air under pressure passes to the branch pipes L and accumulator until the valve I of the cylinder B is floated and closes, and the water under the accumulation of pressure passes by the hole 20 into the cylinder N and gives motion to the valve-moving pistons and valve in the same manner and in the opposite direction before set forth, and during this operation

the water has been running out from the cylinder A through the port 3 and exhaust-port 5, the air entering such cylinder A through the check-valve T, and it will be apparent by these alternating operations the air is compressed in first one cylinder and then in the other by the direct action of the water, and the water-pump can be run at any desired speed and the cylinders A and B can be of any desired size. Hence the pressure of air can be very high, according to the uses to which the compressed air is put, and the cylinders A and B become air-pumping cylinders with water-pistons, and such cylinders do not become highly heated by the compression of the atmosphere, because of the cooling action of the water, and such water as it is run out from first one cylinder and then the other may be received into a vessel sufficiently charged to allow such water to cool before it is used over again.

In cases where a pump is used to compress air to the extent of two or three atmospheres it can be made to operate reasonably well, and hence air under such pressure may be supplied by pipes through the check-valves S T into the cylinders A B, and the powerful compression will be effected by the water in such cylinders A B as it rises, as aforesaid.

It will be apparent that the weights R can be adjusted to any desired position, and the farther the weights are elevated the higher the pressure will have to accumulate before the valves are moved and the greater will be the leverage exerted by such weights in moving the valves, and by adjusting these weights the amount of pressure that accumulates in the cylinders before the valve F is moved will be determined.

It is to be understood that water always remains in the cylinders M N between their stationary heads and stuffing-boxes 15 and the respective pistons O P, and that the passage-ways 19 and 20 are full of water and always remain open into the respective cylinders; but the weights R, acting on the levers, valve-rod, and valve-moving pistons, prevent the pressure of water moving the valves until the pressure in one of the cylinders A or B is sufficient to overcome the resistance afforded by the said weights R and levers Q, and this pressure varies according to the position of the weights on the levers and the leverage exerted by them to hold the valve-moving pistons in a state of rest. When the pressure becomes sufficiently great in one cylinder A or B, (the other cylinder at that time is being discharged,) the water that is forced into such cylinder passes through the port 19 (or 20) and moves the pistons O and P from one position to the other, and the valve F is moved as soon as the levers Q pass the vertical position and are acted upon by the weights to cause them to swing downward and give motion to the valve-rods 13 14 to cause the water-supply to pass to the other cylinder and open the discharge of the first cylinder. The

positions of the weights R can be adjusted so that their leverage will be more or less, and a greater or less pressure will have to accumulate before motion is given to the valve. 5 Hence a safety-valve to the apparatus is not needed, as the cylinders A B will discharge successively and automatically, and should the pressure in the pipes L be greater than that at which the weighted levers Q R are set 10 to move no air will be forced into such pipes L; but so soon as the pressure in the pipes L is lessened the air will be forced in by the successive rising of the water in the vessels A B. The floats 11, being immediately below 15 the valves I, act directly upon them, and when the water accumulates sufficiently to lift the float the valve is closed, and thereby the flow of water from the vessel A or B into the pipe L is prevented, and being confined the water 20 as it is pumped into the vessel causes an increase of pressure and the water goes by the passage 19 or 20 into the cylinder M or N and acts directly upon the valve-moving piston O or P and the weighted levers to change the

position of the valve and direct the water into 25 the other cylinder.

I claim as my invention—

The combination, with a pipe through which water under pressure is supplied, of a valve and valve-chest receiving the water, vertical 30 water-receiving cylinders or vessels, ports leading from the valve-seat to the receiving-cylinders and to an exhaust, air-valves and floats at the upper ends of the water-cylinders, and pipes to convey away the compressed 35 air to a receiver or holder, and valve-moving pistons and cylinders for the same, provided with uncontrolled openings between the respective water-cylinders and cylinders for the valve-moving pistons, whereby the valve is 40 moved to admit water to one cylinder or the other automatically, substantially as set forth.

Signed by me this 4th day of June, 1890.

THOS. C. CRAVEN.
